L. Disbrow,

Sectional Steam Boiler.

Patented Feb. 18, 1831.

Levi Dibbrow of the City & State of New York,
Patented Feb. 18, 1831. Reissued May 6, 1833.
Letters Patent. No. 17. Re. Pat.

The schedule referred to in these Letters Patent and making part of the same containing a description in the words of the said Levi Dibbrow himself of his improvement in the construction of steam boilers, called the combined Furnace Steam Boiler; Patented to him on the 18th day of February 1831. which Letters Patent being hereby cancelled on account of a defective Specification.

To all to whom these presents shall come.

Bout known that I Levi Dibbrow of the City & State of New York aforesaid, have invented a new and useful improvement in the construction of steam boilers, & that the following is a full and exact description of my said improvement called "The Combined furnace Steam Boiler" -

The object of this invention is the advantageous application of coal or other fuel to the purpose of heating water in the boilers of steam engines the water contained in the boiler is heated by means of two or more furnaces of a conical or other form erected within the boiler, having their bases on the grates this which the ashes fall upon or near the same level with the floor of the boiler, The smoke or gas is discharged from the furnaces by one or more cylinders passing through the boiler to its outer surface.

Each furnace is replenished with fuel by means of a tube of cylindrical or other convenient form passing from the outer surface of the boiler thro' the same into each furnace at or near its top.

Each of such furnaces is secured by a door (or other means) at the surface of the boiler & fixed to the furnace with a flange or other suitable connection, and the cylinders above mentioned are also secured to each furnace by a suitable flange or connection.

The said Levi Dibbrow claims as his invention the advantageous application of heat to the boilers of steam engines by means of two or more furnaces for coal or other fuel erected within the boiler itself & as a part of the same invention, he claims the mode of discharging the gas or smoke of the

fuel by a cylindrical pipe or pipes extending from the top of the outer surface of the boiler.

In the annexed plate fig 1. represents the interior of a boiler supplied with a double range of furnaces B.B. of one of which a vertical section is shown D.D. an open mill door at G.G. The grate under each furnace is to be arranged as to be supplied at pleasure into the space below to which the door at F. opens. The smoke from each furnace is discharged through small pipes into the large pipes C.C. which after passing one or more longitudinal thro' the boiler, terminate in one or more chimneys C.C.

Fig 2 represents the transverse section of a boiler partly filled with water with a single range of furnaces. A marks the space not filled with water B. is the vertical section of a furnace, the grate being dropped to empty the contents of the furnace, D is a feeder with its door at G & C.C. are transverse sections of the pipes that discharge the smoke of the furnace.

Another plate X. is annexed showing a ground plan & transverse section of boiler with a double range of furnaces, a transverse section of one with a single range, & a longitudinal section of the discharging pipe & chimney attached.
